UNITED STATES PATENT OFFICE.

HENRY C. HASS, OF FOREST PARK, ILLINOIS.

DESIGN FOR A VINE TRELLIS.

Application filed April 27, 1925. Serial No. 13,227. Term of patent 7 years.

To all whom it may concern:

Be it known that HENRY C. HASS, a citizen of the United States, residing at Forest Park, in the county of Cook and State of Illinois, has invented a new, original, and ornamental Design for Vine Trellis, as shown in the accompanying drawing and described in the following specification.

The single figure of the drawings illustrates my new, original, and ornamental design of a vine trellis.

I claim:

The ornamental design for a vine trellis as shown.

HENRY C. HASS.
